FUEL INJECTION FLOW CONTROL VALVE

Donald C. Scoville, Detroit, Mich., assignor to General Motors Corporation, Detroit, Mich., a corporation of Delaware

Filed Apr. 3, 1958, Ser. No. 726,188

3 Claims. (Cl. 261—23)

The present invention relates to an improved flow control metering valve for a fuel injection system. More specifically the present invention relates to an improvement in the fuel metering valve shown in copending application Serial No. 634,915, McDuffie, filed January 18, 1957, now Patent No. 2,893,711, granted July 7, 1959.

The improvement in the present metering valve consists of constructing the same in a way which makes its operation substantially frictionless which overcomes the hysteresis which has occurred in the control of the previous type metering valves such as that shown in the McDuffie application.

Where sufficiently strong control forces are available under all operating conditions, the previous type metering control valve will function perfectly satisfactorily. However, in the mass air flow type fuel system, shown in the McDuffie case, the forces which will control the actuation of the metering valve are extremely small, particularly under low air flow conditions, therefore, any frictional resistance therein soon reaches a critical value and may, under certain operating conditions, exceed the valve controlling forces.

Accordingly, the present invention is directed to an improved type of metering valve in which a pintle member is mounted on a pair of flexible diaphragms in such a way that the movement of the fuel flow controlling pintle is essentially frictionless and thus fully responsive to even low fuel controlling forces.

The details as well as other objects and advantages of the present invention will be apparent from a perusal of the detailed description which follows.

In the drawings:

Figure 1 is a diagrammatic representation of a fuel injection system embodying the present invention; and

Figure 2 is an enlarged detailed view of the subject metering valve.

Referring to Figure 1, a fuel injection system is diagrammatically represented with only sufficient components to provide a sufficient environment within which to describe the subject metering valve. The system includes an air induction passage 10 having a venturi 12 formed therein and the air flow through which is controlled by a throttle 14. Induction passage 10 communicates with an intake manifold or plenum 16 from which a plurality of individual cylinder intake passages 18 communicate with the individual cylinders of the engine. Fuel nozzles 20 are disposed respectively in each of the intake passages 18 proximate the associated cylinder, not shown.

The flow of fuel to the nozzles 20 is controlled by a metering mechanism indicated generally at 22. The details of metering mechanism 22 as well as other devices which may be incorporated therewith are described in detail in the aforementioned copending McDuffie application. Mechanism 22 will only be described in the present case to the extent required to indicate the operation and control of the subject improved metering valve.

Metering mechanism 22 includes a pair of diaphragms 24 and 26 suitably clamped between a central casing

2

28 and end casings 30 and 32. The diaphragms are respectively connected to the legs 34 and 36 of a U-shaped yoke member 38. Legs 34 and 36 are respectively disposed on opposite sides of a sealed central wall 40 of casing 28. Leg 36 is considerably longer than leg 34 and extends downwardly and terminates in a free end 42. End 42 of leg 36 is adapted to coact with and control the improved metering valve indicated generally at 44. For further details with respect to yoke 38 refer to copending application Serial No. 671,933, McDuffie, filed July 15, 1957.

Diaphragm 24 coacts respectively with casings 28 and 30 to define chambers 46 and 48. Casing 30 has an elbow 50 to which a conduit 52 is connected. The other end of conduit 52 communicates with venturi 12 whereby a vacuum signal proportional to the mass of air flow through induction passage 10 is transmitted to chamber 46. Chamber 48 is open to the atmosphere through a port or passage 54. Thus, as air flow through induction passage 10 increases, an increased vacuum force is transmitted to chamber 46 causing the diaphragm 24 to be moved to the left and, as will later be discussed in greater detail, increase the flow of fuel through metering valve 44.

Diaphragm 26, on the other hand, is exposed to the fuel pressure drop across metering valve 44. As fuel flow through valve 44 increases the pressure drop increases causing diaphragm 26 to urge the valve in fuel flow decreasing direction in opposition to venturi vacuum.

Apropos of fuel pressure actuation of diaphragm 26, fuel from metering valve 44 is admitted to a first chamber 56 defined by casing 28 and diaphragm 26 and acts on the left side of the diaphragm. Fuel from chamber 56 flows through a passage 58 and an orifice 60 to passage 62 where it enters a second chamber 64 formed by diaphragm 26 and end casing 32. Since the chambers 56 and 64 are interconnected by the orifice 60, the fuel flow therebetween will create a pressure differential across diaphragm 26 which is proportional to the rate of fuel flow. Thus, the pressure on the left side of diaphragm 26 will increase with an increased fuel flow rate.

Fuel from chamber 64 will flow to conduit 66 where the same will be delivered to the fuel nozzles 20. Thus the quantity of fuel delivered by metering valve 44 to nozzles 20 is differentially determined by mass air flow and fuel flow such that as mass air flow through venturi 12 increases, the quantity of fuel delivered to the fuel nozzles will likewise increase.

Metering valve 44 can best be considered by referring to Figure 2. The metering valve comprises a casing 70 having an axial fuel inlet passage 72 which is supplied with fuel under pressure through conduit 74 from a pump 76 which in turn draws fuel from a fuel tank 78. Fuel inlet passage 72 terminates in a casing boss 73. Passage 72 communicates with an enlarged counterbored portion 80 of the casing from which an outlet passage 82 is adapted to supply fuel to diaphragm fuel chamber 56.

Casing 70 is further counterbored at 84 to receive a stepped sleeve 86. Sleeve 86 is adapted to fit within counterbore 84 and at one end thereof clamp a first flexible diaphragm 88 between the right end of the sleeve 86 and a shoulder 90 of the counterbore. A cover plate 92 is adapted to clamp a second flexible diaphragm 94 between itself and the left end of sleeve 86.

A pintle member 96 is centrally supported by the diaphragms 88 and 94 and includes a reduced end portion 98 adapted to coact with the flattened end of casing boss 73. In this way end portion 98 controls the quantity of fuel flow through passage 72 in accordance with the axial position of pintle 96. The left end 100 of pintle 96 includes a hemispherical projection 102 which is adapted to coact with free end 42 of leg 36 of yoke 38. To insure the positive movement of pintle 96 in both directions,

a spring clip 104 is suitably attached to pintle 96 and resiliently operatively connects arm 36 and the pintle.

Thus as arm 36 is moved in a clockwise or counter-clockwise direction in accordance with the aforesaid control forces, supra, pintle 96 will move to the left or right to admit more or less fuel to fuel inlet chamber 80. By mounting the pintle upon diaphragms 88 and 94 it is apparent that the axial movement thereof will be frictionless for all measurable purposes.

In addition to constructing the metering valve in a way that it will be substantially frictionless in operation, it is also necessary that the valve be statically balanced. In other words, it is intended that the fuel flow through the metering valve will have no direct effect on the valve to affect the position thereof. As already noted, the valve controlling forces are intended to be limited to those resulting from the actuation of diaphragms 24 and 26. To insure that the valve 44 is statically balanced, the diaphragms 88 and 94 are of different sizes with diaphragm 88 having a smaller effective area than does diaphragm 94.

The effective area differential between these diaphragms corresponds to the pressure drop which will occur in the fuel flowing through the metering valve and more specifically through inlet passage 72 to chamber 80. Due to this pressure drop, the unit pressure acting on pintle end portion 98 is greater than the unit pressure acting on diaphragms 88 and 94. However, the diaphragm area differential brings the resultant and opposing fuel pressure forces acting on the diaphragm into balance leaving the axial pintle position unaffected by fuel flow through the metering valve.

The space 106 between diaphragms 88 and 94 is preferably vented to atmosphere.

Thus the present metering valve construction is such that a frictionless and statically balanced fuel metering valve is achieved which is significantly more compatible with the low control forces available under certain operating conditions than has been any previous type metering valve.

I claim:

1. A charge forming device for an internal combustion engine comprising an air intake passage, a venturi formed in said passage, a plurality of individual cylinder intake passages communicating said intake passage with the individual cylinders of the engine, a fuel nozzle disposed

in each of said plurality of intake passages, and a fuel metering mechanism responsive to the quantity of air flow through said venturi for supplying fuel to said nozzles in proportion to said air flow, said metering mechanism including a fuel inlet passage, a fuel outlet passage, a pintle valve member axially adjustable with respect to said inlet passage to control the quantity of fuel flow therethrough, said pintle being radially supported by a pair of flexible diaphragm members, and a control arm operatively connected to said pintle and adapted to vary the axial position of said pintle in relation to said inlet passage in accordance with the mass of air flow through the venturi, the areas of said diaphragms arranged so that the axial position of said pintle valve member is unaffected by fuel pressure acting on said diaphragms and pintle.

2. A fuel metering valve comprising a first casing having a counterbored portion, a boss extending within said portion, a fuel inlet passage extending through said boss and communicating with said counterbore, a shoulder formed in said counterbore, a pair of flexible diaphragms, a sleeve disposed within said counterbore and adapted to peripherally clamp one of said diaphragms against said shoulder, a cover adapted to clamp the other of said diaphragms against the other end of said sleeve, a pintle member centrally supported on said diaphragms, a control arm operatively connected to and adapted to move said pintle axially within said counterbore, one end of said pintle being disposed proximate said boss for controlling the quantity of fuel flow through said inlet passage, said pintle being exposed to fuel inlet pressure and the diaphragm members being exposed to fuel outlet pressure, said pintle and diaphragm members having different effective areas whereby the axial position of said pintle is unaffected by fuel pressure acting on said pintle and diaphragm members.

3. A fuel metering valve as set forth in claim 2 in which the unit fuel pressure acting on the pintle and smaller diaphragm is substantially balanced by the unit fuel pressure acting on the larger diaphragm.
